Thomas Spalding, McIntosh, Co Georgia 8104X

My Patent.

The schedule referred to in the Letter Patent and making part of the same containing a description in the words of the said Thomas Spalding himself of his improvement in Generating Steam

It all to whom these presents shall come: Be it known that I Thomas Spalding of the County of A. M. McIntosh and State of Georgia have invented a new and useful improvement in generating Steam and the following is a description of the same ^{the vessel is} invented and improved by me. The vessel is to be round or long as may be desired or required and in external appearance ^{will} resemble any other boiler now in common use, but the bottom will consist of two plates, either copper or iron as may be desired kept apart from each other by a hoop of the same metal of which the plates of the bottom may be composed and the bottom may be made either of cast or wrought copper or iron at will and around this bottom there shall be a strong iron hoop will pass and be secured to it in the strongest manner by screws equal to any pressure of steam that may be required or desired. The upper parts of the vessel will be composed first of a casing in the common form of the Boilers of either copper or iron or turned iron or cast iron or in fine of my metal which will contain water and be watertight at the necessary temperature for generating steam and over this will be laid hemp or flax or cloth made of hemp or flax or cotton or will be covered with paste or glue animal or vegetable as many foldings of the cloth as the material of which cloth is made as may give a perfect security against the possibility of bursting under any pressure that can be possibly required in any useful mechanism for it was long since performed in a series of experiments made by men of science under the direction of the government of France that hemp kept together with glue was one third stronger than the wood which

now and twice as strong as a bar of English iron of the same size
 over all these several envelopes a light knit web of copper or iron as
 well for ornament as to keep from injury the outer coating of the boiler
 may be placed and which would show to the spectator any extraneous
 pressure from within. From the upper plate of which the bot-
 tom of the boiler is formed tubes of the same metal as mentioned
 may be desired communicating with the space left open between the
 two plates of which the bottom is composed pass up thro' the water and
 open into the air above & thro' the top of the Boiler. The Boiler is
 supplied with water and furnished with safety valves &c all other
 apparatus necessary either for use or security. The intermediate space
 between the two plates of the bottom is filled with tallow or any other
 animal or vegetable oil or intermedium that is capable of readily燃
 ing and readily communicating to the water above it separated by the
 upper plate and by the pipes from the water contained in the boiler but
 impeding to it the high temperature which it is capable of reach-
 ing. The tubes that pass from the intermediate thro' the upper cov-
 ering of the boiler will strengthen and preserve it from collapsing in
 any neglect of the engineer. which the intermediate communicating
 with the atmosphere if the water in the boiler should be from carelessness
 allowed altogether to evaporate would then but not until then
 throw off the vapor and thereby thereby by the absence of steam that
 there was no water remaining in the boiler to take off the redundant
 heat contained in the intermedium. Tallow and other animal or
 vegetable oils have been preferred because in giving out their vapour
 in the absence of all water in the boiler where they would give an
 admisitely sound sufficient to alarm any passenger in a steam
 Boat or other machine connected with it. It will be seen that
 by this arrangement of tubes filled with tallow or other intermedium
 all the power of Stephenson's Patent Boiler will be obtained without
 their being subject to being destroyed by the passage of the flame thru
 them.
